MACHINE FOR SEALING AMPOULES
AND THE LIKEJames F. Kahlenberg and Herman H.
Kahlenberg, Sarasota, Fla.

Application November 24, 1947, Serial No. 787,654

16 Claims. (Cl. 49—7)

1

This invention relates to machines for sealing ampoules, ligature-tubes and other tubes and containers of glass or analogous material, generally such as are at least partly filled before sealing, and usually such as contain pharmaceutical products. The class of machine to which the invention belongs consists of a circular carrier or holder within the periphery of which are provided recesses for holding the ampoules, or other tubes, and a gas burner torch to which the carrier conveys the ampoules and submits them to such torch for sealing by heat. There have been developed in the art various means for cooling the ampoules, as by a continuous stream of water flushing the carrier, or cooling current of air after the heating and sealing are effected; forms of torch or burner in which the flame sweeps in waves across the ampoules in an upward slant, or by which the tops thereof are heated by separate successive applications of heat to the same ampoule cumulatively; devices for step-carrying the ampoules at fixed intervals to the burner and holding each one there for a fixed uniform period of time for sealing; none of which expedients have we found desirable to embody in our machine; nor the recently advanced mechanisms for gripping and twisting the ampoule tops in sealing, in lieu of manual manipulation as customary.

The object of our present invention is to provide a sealing machine which will reduce the amount of mechanism required for the performance of its functions, to an irreducible minimum somewhat more in consonance with the lightness of the task involved, so that much of the complicated and costly machinery employed in some of the better grades of apparatus may be dispensed with altogether. Many laboratories do too little of this work of filling ampoules to justify buying a large and expensive apparatus for the final step of sealing, with added excessive operative and maintenance personnel and upkeep, and have continued, or reverted to, wholly manual sealing by such burner alone; although with a proper machine both greater efficiency, uniformity, certainty, and vastly fewer spoiled ampoules can be attained. It is our purpose to produce a machine in which these advantages can be achieved, in which the reliability of effective mechanism shall be combined with the use of the directive brain, initiative, judgment and experience of the operator; in which there shall be no cut and dried sealing time dictated by the machine regardless of the fact that correct sealing time varies largely with each ampoule sealing; in which the same mind that decides that

the ampoule is completely sealed, shall also have determined how long to continue that sealing operation; in which more effective provision shall be made for avoiding deleterious overheating of the ampoule, preventing vaporization of contents, formation of bubbles in the glass while sealing, with consequent leakage, and spoilage, a major cause of rejects and loss; a machine which will comprise so few parts and motions that anyone who knows what he wishes to do with the ampoule can readily learn to operate it, and entrust its operation to another easily instructed for occasional handling in the absence of the regular worker; and in which certain of the features heretofore used in such sealing machines which we deem unnecessary or undesirable may be wholly eliminated; all within a cost that will permit its wise acquisition by small laboratories unjustified hitherto in purchasing more elaborate equipment.

With these and other subordinate objects in view, our invention consists in a machine in which first all the usual machinery, for rotating the ampoule-carrier by connections between the carrier-shaft and the motor-shaft, all mechanism operating directly upon the said carrier itself to rotate it in any way or degree, are altogether eliminated permanently from our machine, the carrier is thus initially left entirely free of all forces acting upon its turning, and concomitantly is without any restraint of such mechanism upon its rotation, can be spun around freely by a finger-touch of the hand, almost effortlessly upon its ball bearings, and does not actually operate to rotate said carrier until the ampoules are inserted in their places therein, and does not continue to operate when they are removed therefrom, but automatically ceases to turn, by the absence of said ampoules therefrom, a single mechanical instrumentality being devised to rotate the ampoule in its recess or socket while being heated and sealed, and just prior thereto, and thereby consequently to rotate the carrier which brings the ampoule to the burner and conveys it off after sealing, the rotatory motion imparted to the ampoules being in part translated into rotatory motion of said carrier by friction of the ampoules with the sides of the recesses or sockets in which they lie; second, embodies means for simultaneously retaining the ampoules in situ during such rotatory motion thereof and for adequately engaging the inner sides of said recesses so as to effectually convert such rotatory motion directly applied to the ampoules into rotatory motion of the carrier, without loss of

2

power or motion in transition; third, means likewise for simultaneously checking the rotation of the carrier at the will of the operator and amplifying the rate of rotation of the ampoule being heated and sealed, while others of the ampoules not yet ready for heating, or already sufficiently past the heating locus after sealing, remain more or less unrotated, the one ampoule which is being heated and sealed at the moment being held stationary at its top at the termination of the operation of sealing by the operator during said moment and during said amplified rotation of its main body as stated; fourth, comprises an improved system for heating the sealable top of the ampoule by the gas burner flame projected across its rotating surface at one angle from the torch to soften the same to a pliable and fusible consistency, while at the same time an air jet is fixed to project across at a preferably opposite angle and directed upon a point below the sealable top, as the neck of the ampoule, to interpose a cooling agent of whatever strength is needed (and this the operator, or the owner of the machine who employs him, can determine), not only after the sealing operation to harden the glass as sealed, but during the heating of its top, to maintain such temperature condition of the body of the ampoule as will restrain its contents from overheating, vaporizing, forming glass bubbles and rejects, yet not so low as to create too great difference between top and bottom and thus cause cracking of the ampoule with like spoiling; fifth, provides means permitting the lifting out of the sealed ampoules after sufficiently cooled to touch, as well as means for automatically removing all that are not manually lifted out and replaced with others right after sealing; sixth, eliminates all necessity for a mass of separate vertical shafts, one for each ampoule, holders, rollers, and other machine elements; seventh, contains so few elements that there is little or nothing to get out of order, or require replacement except small matters.

Our invention further consists in the novel general construction, arrangement and combination of elements and parts which enable us to dispense with such undesired or unneeded mechanism and complication as hitherto required by this class of machines, and which create the greater efficiency, smoothness of operation, quickness and quantity rate of sealing, lowered rejects, lowered initial cost of both the machine and its maintenance and operative expense, simplicity and fewness of separate parts, ease of their assemblage and finishing, handling and portability of the device, durability and indisposition to get out of order, which characterize our said invention as demonstrated in its actual practice.

While its very simplicity negatives largely any great range of alterability without sacrifice of some of its objectives, we have found some minor variations possible and there may well be others worthy of adding, or some equivalent modifications. We are presenting in our drawings and this specification what we have after experiments determined to be the preferred embodiment of our invention, which we deem to embrace any and all structures falling within the purview thereof, as expressed in our statement of its objects and specific essence hereinabove outlined, and as hereinafter more fully described, and both broadly and particularly defined in the appended claims.

In the accompanying drawings forming part hereof, in which like numerals of reference designate corresponding parts in the several views:

Figure 1 is a plan view of our newly-invented machine, ready for operation.

Figure 2 is a similar plan view, with the upper plate of the carrier removed, with the addition of the chute for carrying off the sealed ampoules, and with the gas blast, air blast and belt mechanism omitted.

Figure 3 is a side elevation, partly in section, the carrier being shown in a central vertical cross section through said carrier on the line 3-3 of Figure 1, with belt pulleys omitted.

Figure 4 is an enlarged detail view of part of said carrier, with an ampoule placed therein, being a section on the line 4-4 of Figure 1, only certain of the disks being shown.

Figure 5 is a similar enlarged detail view showing similar parts of the carrier, with the ampoule dropping from its pocket or apertures in the carrier after sealing and reaching a point of exit, the chute being broken off; the section being taken upon the line 5-5 of Figure 1.

In the construction of our invention, we have made it in the form of a comparatively small portable apparatus, to which its simple elements are well adapted, the example shown in the drawings being a machine of approximately 16 inches by 12, but any size of apparatus can be chosen, depending upon the quantity of work and the capacity thereof. We provide a suitable frame 1, comprising a table, or platform 2, a parallel floor 3, with ends 4 supporting the table 2, which ends do not have to be solid, and may be corner posts only. The frame is preferably open on all sides, and adapted to rest upon any surface arranged at any suitable height, for operation. Upon this framework, just above the said table 2, we mount a circular carrier 5, rotatable on or with a small stub shaft 6, set on a vertical axis in the table 2, and is shown held therein by the nut 7.

The carrier consists of a top disk 8, provided with 12 or other number of apertures 9 each of a size to receive an ampoule vertically inserted, a lower disk 10 of like size, a spreader 11 between the two disks, said spreader being of less diameter than the disks, so as to permit the ampoules to lie around the periphery of the spreader when standing in the apertures 9. The lower disk 10 also is provided with 12 apertures 12 or other number corresponding with the apertures 9, but these apertures 12 do not align perfectly with the apertures 9 immediately above them, for a purpose to be explained hereinafter, but are each set slightly advanced, in the direction of rotation of the carrier, with respect to the aperture directly above. The disk 8, disk 10, and spreader 11 are all secured to a locking disk 13, with spreader 14 between. This disk may be approximately half the diameter of the upper carrier disk 8, though not necessarily, and is provided with a number of serrations or notches 15 in its edge, corresponding with the number of ampoule apertures 9. At the rear of the machine is located a locking lever 16, preferably spring-actuated, with any desired and usual form of spring-rod-handle 17, normally engaging the edge of the disk 13, and fitting into its serrations or notches. The carrier assembly thus described, is mounted centrally upon this stub 6, and rests upon ball-bearings 18 affixed to the table or platform 2 and the several disks and spreaders are secured together by bolts or pins 19 passing through the same. An annular stationary plate 20 surrounds the locking disk 13 and its spreader 14, sufficiently above the disk 13 not to interfere with the working of the locking lever 16. At a

suitable point, the stationary plate 20, which supports the ampoules in their position in the apertures 9 and 12, is provided with an exit aperture 21, preferably of slightly wider diameter than the said apertures 9 and 12, to permit easy escape of the ampoule through said opening in the stationary plate into a chute 22 below, the chute being broken off and but partly shown, since it is of usual form and may lead to any convenient discharge point.

Somewhat opposite to the aperture 21 in the plate 20, we mount in the table 2, upon a vertical axis, a drive pulley 23 and an idler 24, with an elastic and flexible belt 25 surrounding them, and bearing frictionally upon one or more of the ampoules which are placed in the apertures or sockets 9 and 12 of the carrier. The belt is preferably of round cross-section, and by frictionally engaging the outer surfaces of the ampoules, said belt will, when in motion under correct adjustment of power and contacts, not only rotate the ampoules with which it is in immediate engagement, but also rotate the carrier containing them, when the machine is in motion, as will herein-after fully appear. The belt is arranged at a height to contact the body of the ampoules in juxtaposition to it. Beneath the table 2 or elsewhere as found convenient, is set an electric motor 26 with reduction gears 27, which motor is plugged into the nearest electric light or power socket. The details of this motor, its plug, its connections to the drive pulley, etc., are not shown, they being of any usual or desired form, as supplied for such purposes as this machine.

Above the pulleys are located the gas burner 28, provided as usual with a gas source 29 and air source 30, all other details being omitted as not differing from those commonly used. The gas burner has its torch or jet directed diagonally at a fixed point at which an ampoule will be brought to position for sealing, though of course there is nothing to prevent setting it movably if it is desired to do so. Opposite to the gas burner 28 is an air-nozzle or source of air blast 31, directed diagonally at the same fixed point as the gas burner, but at an opposite angle, to cut across the direction angle of the heat or flame of the burner. This air nozzle is set lower than the gas burner, so as to strike the neck or body of the ampoule whereas the gas flame is to bear upon the upper end thereof. The usual stop cocks of the gas jet and the air jet will offer sufficient regulation of the quantity and force of current of heat and air respectively, but any further adjustment means may be added, if desired.

It will be observed that we do not provide separate means for rotating the carrier, independent of the means for rotating the ampoules while sealing them, as is customary in apparatus of this character, no ice-water sources for chilling the carrier, by fluid of low temperature bathing the bases of the ampoules thereby, no mechanisms for establishing uniform time for submitting each ampoule to the process of sealing, and automatically submitting another one at the instant the time is up for the preceding ampoule, no machinery for applying at an instant of pre-arranged heat-shutoff, fixed devices for operating mechanically upon the top of the ampoule with pre-arranged appliances for completing the sealing by automatic gripping of the ampoule top, by a system of machinery designed to execute that action. We believe when the mode of operation of our machine is studied, it will be seen

that we effectively perform all necessary functions of such an apparatus as this, with no more machinery than the simple construction above outlined.

The operation will be readily understood by those who know the present means of sealing ampoules by hand or by any of the apparatus of the present art. The motor having been plugged in, and the gas blast and air blast having been set as desired, the drive pulley 24 will operate to run the belt in the direction indicated by the arrows in the drawings. The carrier will not, however, rotate, since there are no ampoules in the same. The ampoules having been duly filled or partly filled up to the point or level desired, are now inserted in the apertures or sockets 9 in the upper disk 8, and drop easily into the apertures 12 in the lower disk 10, and come to rest upon the stationary plate 20. If the drive pulley is running, the carrier is locked in position against turning, by letting the locking lever 16 be engaged with one of the serrations of the locking disk 13. These are so arranged relatively to the apertures 9 and 12 of the carrier, that when said locking lever 16 is in projected position, and set in one of the serrations, an ampoule is held at the right point for sealing by the torch or burner, and for cooling by the air current. The ampoules can be inserted in the carrier whether the belt is running or not, but if inserted at a point where they will contact the belt, the disk 13 should be locked first. If this is done, then the contact of the belt will rotate only the ampoule or ampoules which are engaged frictionally by the belt. But when the carrier is not locked, and is free to turn on its ball bearings, the friction of the belt will in rotating the ampoule or ampoules contacted thereby, also rotate the carrier by pushing the ampoules along with the motion of the belt, and causing them to press against the inside of the apertures 9 and 12 in the disks 8 and 10, and carry the carrier along with the belt, much as though the outer surfaces of the ampoules were a periphery to the carrier body.

In this rotation of the ampoules by the belt, and the further rotation thereby of the carrier itself, it will be noted that upon locking the disk 13 with the locking lever 16, the action of the belt will be solely the rotation of the ampoule directly upon its own vertical axis in the carrier. It has been stated, and shown in the drawings, that the aperture 12 in the lower disk 10 is offset or advanced relatively to the aperture 9 immediately above it in the upper disk 8, being set forward in the direction of travel of the belt. The amount of this offset is not necessarily great. It may be five degrees from the vertical or even less. Its object is chiefly to hold the ampoule in its pocket or socket formed by the two nearly aligned apertures 9 and 12. Without this offset, there is a tendency of the belt's friction to lift the ampoule out of its pocket, but with this offset, expedient, the ampoule remains properly in situ. This lifting effect is present when the carrier is locked, and only the ampoule rotated. It also is present when the carrier is released and is being rotated by the belt through the instrumentality of the ampoules, and not only is the offset effective to hold the ampoule against lifting, but it operates to press it further down into the pocket and likewise assist the rotation of the carrier under the friction of the belt upon the ampoule surfaces. The number of ampoules contacted simultaneously by the belt will depend largely

upon the location of the pulleys and belt relatively to the segment of the carrier disks coming within their influence. Obviously, the more ampoules contacted, the more rotatory power present; yet with good ball bearings, the carrier herein shown and described will rotate under belt-impact upon even one ampoule.

The essence of our invention is that we first eliminate all the old-style mechanisms that made the carrier rotate by connecting gears and the like from motor to carrier, and all the separate vertical shafts, one for each ampoule to be rotated, all the holders to rotate said ampoules, the rollers or other devices which not only required much motor power and gears to produce such rotation of the carrier, but also in themselves actually exercised a restraint or brake upon the said rotation of the carrier's free movement of itself. By freeing the carrier initially of these restraints, we have found that said carrier, on its ball bearings, can be spun by a finger-touch of the hand, and therefore the actual power to operate it then becomes very little. Then by locating the ampoules in the pockets of the carrier directly, with the belt gripping the exteriors of the ampoules above the line of the pockets as shown, and the lower part of said exteriors gripping the inside of the said pockets, it is really only necessary to apply such power to one or two ampoules to impart adequate carrier motion while the machine is unchecked by the spring locking stop, and when the machine is empty of ampoules, there can be no motion of the carrier by the operation of the motor, there being no connection between the motor and said carrier until the ampoules are inserted in the carrier to be contacted by the belt. It will be noted by reference to Figure 4 of the drawings, that the ampoules are not always or wholly perpendicular in the recesses in the carrier, but by reason of the offset or advancement of said recess in the direction of travel of the belt and the carrier, there results a slight diagonal incline of the upper end of the ampoule in that same direction, which tends to lock the bottom of the ampoule against the side of the recess or pocket. This not only provides the necessary friction and leverage of the ampoule against one side of the pocket interiorly, but it enables us at the same time to insert and remove the ampoules freely, since they do not become stuck in said pockets, neither loose enough to be pulled out.

With this manner of operation of the carrier understood, we will now proceed to the actual sealing. The ampoules being filled, and the carrier locked by the lever 16, a given ampoule stands in its pocket at a point where the gas flame and the air current will both strike it at the portions thereof designed to receive them. The belt rotates the ampoule upon its own axis, and the air current from the nozzle 31 plays upon its neck or main body, in fact has already been doing so perhaps as the carrier was rotated to bring the ampoule into place, or while a preceding ampoule was being sealed, and the present one awaiting its turn. This air current maintains a required temperature low enough to ensure against ill effects in sealing previously mentioned, but not so low as to create too great a differential of heat and cold which might induce brittleness. The operator turns on the proper flame from the gas burner, which heats the upper end of the ampoule all around as it rotates, and sufficiently softens the glass to render it pliable and sealable. The operator of long experience knows the right

condition from the color of the heated glass top, and the newer operator soon learns to detect this after a few trials perhaps of empty ampoules or under guidance. The moment this condition appears, he seizes the top of the ampoule with the usual grippers or form of pliers customarily employed in hand sealing, and holds the said top of the ampoule while it is still being rotated by the belt, for just the necessary few seconds to let the rotating ampoule top twist around on itself, completing the sealing operation, effected automatically by such rotation under the gripping; in which action usually a small fragment of glass is twisted off and discarded. Immediately, the operator pulls out the locking lever 16, releasing the carrier, and the belt rotates the carrier to withdraw the sealed ampoule from the flame (which can be turned off or away if desired, or left on for the instantly following sealing of the approaching ampoule) and when the new ampoule is in position, the operator releases the lever, locks the carrier again, and repeats the operation upon said next ampoule. The process of sealing a number of ampoules in quick succession may be carried on without interruption, and without shutting off the burner and nozzle, as fast as desired, within the limits of the actual time needed for the heating, twisting, releasing, and within the efficiency of the operator.

While the second ampoule is heating, the sealed ampoule which has been under the cooling influence of the air current from the nozzle 31, which counterbalances any conduction of heat from the burner and warm ampoule-top to the contents, soon becomes cool enough to be handled or removed. The importance of this air current is considerable and vital. Without it, the body of the ampoule would get hot, the contents possibly damaged, perhaps vaporized and a bubble set up in the neck of the ampoule or in the top being softened and sealed, which is a very frequent cause of spoilage and rejects, as stated. It also avoids the need for cold-water currents in the carrier body, which require mechanism for continuing the flow thereof, means for icing the same, constantly, and make a rather sloppy job of the sealing, particularly where, as in our invention, a rubber belt is employed in contact with the ampoules, which would have a tendency to make the belt slippery and impair the operation. It is also important that this air current, which has not been employed as a cooler during heating and fusing in devices of this class, should be arranged as we have it, beneath the gas blast and from an opposite angle, and directed at the neck of the ampoule, with the gas blast centered on the apex thereof; though minor variation of the arrangement may doubtless be quite possible without disadvantage.

After the ampoule is sealed, and in the rotation of the carrier, conveyed further away from the sealing point, it quickly cools and may, in our apparatus, either be removed by hand, lifted out and placed in a receptacle, or it may be allowed to travel to the point where the exit aperture 21 is made in the stationary plate 20, and to drop into the chute there provided. As fast as the sealed ampoules are removed from the carrier, the operator replaces them with others needing sealing, and so the operation of the machine may continue uninterruptedly, until all the ampoules required are taken care of. We do not however, confine ourselves completely to this novel device of two alternative exit or removal,

means, and we may make our machine with one or other of these expedients, or with both, as shown and herein described.

What we claim as new and desire to secure by Letters Patent is:

1. A machine for sealing ampoules, of the class in which a rotatable carrier conveys the partly filled ampoules to a point of sealing where a heat means fuses and permits the sealing; which comprises a circular carrier constructed and arranged to be initially and primarily free to spin and turn without restraint while empty of ampoules provided with pockets in its periphery for holding the ampoules in a vertical position, a heat means to which the carrier conveys said ampoules for sealing a single, rotating means for simultaneously by the one single rotating means free of any extra mechanism rotating the ampoules by direct contact of said means with the outer surface of an ampoule or ampoules contained in that portion or segment of the carrier which is contiguous to the heating means, and also through the instrumentality of said ampoules then being rotated which frictionally engage the sides of the pockets, and which are carried along by and with the said rotating means, rotating the carrier itself without separate mechanism therefor, whereby only the ampoule or ampoules contiguous to the heat means and sealing point are rotated, and whereby the said carrier is rotated only at the time when it contains ampoules therein; and means for momentarily stopping the carrier when an ampoule, desired to be sealed is directly at the sealing point, and thereby applying whatever power of the rotating means has been theretofore rotating both the ampoule and the carrier, into faster or stronger rotation of the ampoule while being submitted to the heat means, for greater uniformity and ease of sealing.

2. A machine for sealing ampoules which comprises a rotatable carrier constructed and arranged to be initially and primarily free to spin and turn while empty of ampoules having pockets therein for containing the ampoules, a heat means to which the carrier conveys the ampoules for sealing a single rotating means for rotating single rotating means free of any extra mechanism the ampoules when contiguous to the heat means and sealing point and for rotating thereby through the instrumentality of such ampoule-rotation, the carrier holding said ampoules, the said rotating means consisting of a driven friction-belt located adjacent the sealing point, which belt engages the outer surface of an ampoule or ampoules and frictionally rotates the same upon its own vertical axis, and concomitantly through said ampoule-rotation rotates the carrier; by friction of said ampoule upon the sides of the pocket containing it; and means for momentarily stopping the carrier when an ampoule to be sealed reaches the sealing point, while the belt is still running, and thereby apply whatever power of the belt has been previously rotating both the carrier and the ampoule, into rotation of the ampoule axially while being sealed.

3. A machine for sealing ampoules, of the class in which a rotatable carrier conveys ampoules to a heat means for sealing, comprising in its construction a rotatable carrier provided with pockets in its periphery for containing the ampoules and constructed and arranged initially and primarily free to spin and turn without restraint while empty of ampoules, a heat means arranged adjacent a chosen segment of said

carrier as a sealing point, and a single driving instrumentality located between said heat means and carrier, for concomitantly and also alternatively rotating the ampoules by direct contact therewith and only as they approach and reach the said sealing point and are conveyed away therefrom, consisting of a driven friction-belt arranged to contact the outer surface of one or more of the contained ampoules and axially rotate the same, and thereby through said ampoule-rotation and its friction with the sides of the pockets, rotate the carrier solely through said engagement with said outer surface of said ampoule or ampoules contiguous thereto and through said friction with the insides of the pockets, whereby the said carrier is carried along with said ampoules as they turn within the pockets, without the aid of any impact upon or contact of any rotating means with the carrier itself or any part thereof, and whereby the said instrumentality does not rotate either said carrier or any part thereof until the ampoules are inserted in the pockets contiguous to the sealing means.

25 4. In a machine for sealing ampoules, the combination, with a sealing means located at a selected point to which the ampoules are to be conveyed, and a single rotating means constructed and arranged to be the sole operative means for both rotating the ampoules and for 30 rotating the carrier, through the instrumentality of said ampoules, and consisting of a driven friction-belt adapted and arranged to contact the ampoule or ampoules contiguous to said sealing point, of a rotatable carrier provided with pockets to contain the ampoules, located at the periphery of said carrier so that the friction belt contacts the outer surface of said ampoule or ampoules, to axially rotate the same and the pockets being formed integrally in and part of the said carrier whereby the ampoules frictionally contact the insides of said pockets also rotate the carrier thereby; the said pockets being so constructed that one portion of the said pockets is offset or advanced relatively to the other remaining portion of the same pocket, whereby the frictional engagement of the belt with the outer surface of the ampoule will seat it further into the pocket, and give it a greater frictional 45 hold upon the inside of the pocket whereby more effectively to cause the rotated ampoule to rotate the carrier under the power of the belt.

5. A machine for sealing ampoules which comprises in its construction a rotatable carrier having pockets at its periphery for containing ampoules, a sealing means to which the carrier is arranged to convey the ampoules, a single means for rotating the ampoules by direct contact of the same upon the ampoules and through said 55 rotation of the ampoules causing the rotation of the entire carrier by friction of the ampoules with the insides of the pockets therein, and consisting of a driven friction-belt in engagement with the outer surface of the ampoules to rotate the same axially and also the carrier; the pockets each being offset in the lower portion of the same by being advanced an appreciable amount in the direction of travel of the belt, whereby said belt in its travel and engagement with a contacted 60 ampoule in said pocket, seats the same further into the said pocket, prevents its rising, and also better rotates the carrier the pockets being formed integrally in and part of the said carrier.

6. A machine for sealing ampoules which comprises in its construction, sealing means, a driven

friction belt near the point of sealing, a rotatable carrier provided with pockets therein to receive the ampoules in vertical position to be rotated by contact of the friction belt with the exterior thereof; the said belt being in contact with the exterior of an ampoule or ampoules to rotate said ampoules and through the said rotation of said ampoules causing the rotation of the entire carrier by friction of the ampoules with the insides of the pockets therein the said pockets being offset at bottom relatively to the top, whereby the belt seats them securely in said pockets while rotating; the said pockets being formed integrally in and part of the said carrier, and the friction belt being the sole rotating means of the machine, and operating to turn the carrier solely through the turning of the ampoules.

7. A machine for sealing ampoules of the class in which a rotatable carrier conveys the ampoules to a place of sealing, a heat means directed at the tops of the ampoules, a rotatable carrier provided with pockets for the ampoules, a single operative means for simultaneously rotating the ampoules and thereby the carrier without separate means for either and without intervening additional mechanism consisting of a single driving belt contacting solely the outside surfaces of the ampoules, and directly contacting those ampoules which are contiguous to the sealing place and thereby rotate the carrier as well as the ampoules contacted and seat said ampoules frictionally in engagement with the sides of the pockets inside, and cause them to carry the carrier along and around with said belt to bring the contacted ampoules to the sealing place, and a cooling air nozzle near the sealing place, directed at a point below the tops of the ampoules being heated and sealed, and adapted to play a current of cool air against the necks of the ampoules while the heat means is acting upon the tops, to intercept said heat blast at said neck of the ampoule being sealed and prevent the heat from expanding or otherwise affecting the contents of the same, and causing air bubbles in said neck and the sealed top of the ampoule.

8. A machine for sealing ampoules, which comprises the combination of a rotatable carrier having pockets to receive the ampoules in vertical position, and adapted to convey the ampoules to a point of sealing; a driven friction-belt located at the point of sealing, and arranged to contact the outer surface of one or more ampoules at and near the said point of sealing and rotate the same axially while being sealed, and also rotate the carrier which conveys them there and away; and separate heat means and air blast means arranged near the sealing point, both above the said friction-belt, and both directed at the same ampoule; the heat blast being directed at the tops of the ampoules to fuse the same, and the air blast being directed at a point below the heat blast and approximately at the neck of the ampoule then being heated and sealed, whereby to intercept the heat current at said neck, and prevent or counterbalance its heating effect extending injuriously or excessively to the said neck and lower main body of the ampoule while being sealed; the said pockets being formed integrally in and part of the said carrier, and the friction belt being the sole rotating means of the machine, and operating to turn the carrier solely through the turning of the ampoules.

9. A machine for sealing ampoules which com-

prises in its construction a rotatable carrier formed of an upper circular disk provided with apertures in its periphery, a spreader of reduced diameter beneath the same to allow the ampoules to enter said apertures, a lower disk corresponding to the upper disk and provided with similar apertures almost aligning with the ones in the upper disk, but appreciably offset and advanced in the direction of rotation of said carrier, a locking disk of reduced diameter below said lower disk, with spreader between, and serrated upon its periphery in such arrangement as to be spaced to hold the ampoule being sealed at the sealing point, a locking lever adapted to engage said disk and enter one of said serrations so as to hold said carrier at the exact position for maintaining an ampoule at the sealing point, and a stationary bottom plate on which the ampoules rest, said carrier being mounted upon a vertical shaft to rotate horizontally, and provided with suitable exit means for discharging the ampoules or removing the same after sealing; a driven friction-belt located at one side of the carrier to operate in connection with a segment thereof, and bearing upon the outer base of one or more ampoules of said segment to turn them axially in their pockets and also through their instrumentality rotate the carrier to convey them to the sealing point when the locking lever is out of engagement with the serrations of the locking disk, and, when said carrier is locked stationary by said lever, to rotate more speedily or effectively the ampoule being sealed, whereby when it is gripped by the operator at its fused top and rotated by said belt axially, it will twist and seal; and separate heat means and air nozzle mounted above said belt, the heat blast being directed at the top of the ampoule being sealed, and the air nozzle being directed at the neck of the same ampoule to keep the lower body, neck and contents of the ampoule cool while being sealed; the said pockets being formed integrally in and part of the said carrier, and the friction belt being the sole rotating means of the machine, and operating to turn the carrier solely through the turning of the ampoules.

10. A machine for sealing ampoules, which comprises in its construction an ampoule-conveying carrier formed with an upper disk provided with apertures, a lower disk similarly apertured but not exactly aligned with the apertures above, being offset or advanced in the direction of travel of the carrier sufficiently to allow the axial rotation of the ampoule to seat it more securely in the carrier-apertures in the two disks, reduced spreaders between the disks and beneath the same, a reduced locking disk peripherally serrated, and a stationary bottom plate, the carrier being mounted upon a vertical shaft inside the stationary plate; a locking lever under control of the operator to stop the carrier by engaging the locking disk; a single driving instrumentality consisting of a driven friction belt bearing upon the exterior of one or more of the ampoules located in contiguity with the carrier and arranged to contact the outer faces of the ampoules adjacent the same and both axially rotate the ampoule contacted and when the carrier is free of the locking lever also rotate the same solely through the rotation of the ampoule or ampoules contacted and by the friction thereof with the sides of the carrier apertures in the two disks, and continue to rotate the ampoule set at the sealing point when the carrier is locked.

13

by the operator by the lever; and heat means directed at the top of the ampoule being sealed and air cooling means directing a current of air upon the neck of the ampoule simultaneously; the said pockets being formed integrally in and part of the said carrier, and the friction belt being the sole rotating means of the machine, and operating to turn the carrier solely through the turning of the ampoules.

11. A machine for sealing ampoules of the class in which a rotating carrier conveys the ampoules to a heat means for sealing them, which comprises a rotatable carrier adapted to receive ampoules in vertical position; means for holding said carrier stationary at the control of the operator, said carrier being adapted to be rotated normally when the operator releases said holding means; a single instrumentality power-driving means consisting of a driven friction belt bearing upon the exterior of one or more of the ampoules adapted by contact with the surface of the ampoule or ampoules contiguous thereto not only to axially rotate the ampoule or ampoules when the carrier is locked by the operator, but also when the carrier is unlocked, to rotate said carrier through the same contact of the driving means upon the surface of the ampoule or ampoules; and heat means directed at the top of the ampoule and air cooling means directed simultaneously upon the neck of the same ampoule; the said pockets being formed integrally in and part of the said carrier, and the friction belt being the sole rotating means of the machine, and operating to turn the carrier solely through the turning of the ampoules.

12. A machine for sealing ampoules, comprising a heat means, a rotatable carrier having apertures forming pockets for ampoules, means for holding said carrier stationary at the control of the operator; a single instrumentality driving means consisting of a driven friction belt bearing upon the exterior of one or more of the ampoules adapted by contact with the surface of the ampoule or ampoules to axially rotate the ampoule not only when the carrier is stationary, but also when it is unlocked, to rotate the carrier through the same contact of the belt upon the ampoule; and means whereby the frictional engagement of the belt upon said ampoule-surface will seat it further into its pocket and give it a greater frictional hold upon the inside of the said pocket, to better rotate said carrier and prevent rising of the ampoule in said pocket.

13. A machine for sealing ampoules, comprising a sealing table equipped with heat source, a rotatable carrier formed with peripheral recesses directly in said carrier, each formed and shaped and sized to have ampoules fitted directly into them without the aid or intervention or addition of any secondary devices whereby to be engaged frictionally with the insides of said recesses sufficiently to turn the said carrier by gripping the exteriors of the ampoules and imparting a thrust to the same; a power source equipped with pulleys connected therewith, and normally unconnected with said carrier, the said carrier being freely spun or turned by the finger, unrestrained by any mechanism; the pulleys being connected by a friction-belt mounted contiguous to the sealing means and out of contact with any and every part of the carrier or mechanical adjunct thereof, while the machine is empty of ampoules; the said belt being after the ampoules are inserted in the recesses, in frictional contact solely with the exterior of an ampoule or ampoules located,

in the direction of travel of said belt, on the way to the sealing means of the machine; whereby first to rotate only the ampoule or ampoules contiguous to and so approaching said sealing means, and secondly, solely through said frictional contact with the exterior of said ampoules and the frictional contact of the bottoms of said ampoules with the insides of the recesses directly in the said carrier, cause the mere rotation of said ampoule or ampoules in their pockets to impart a translatory rotatory motion to the carrier; stop means of suitable form to check the carrier at will at the point of sealing; the whole machine being automatically normally unoperated and self-stopping as to said rotation of the carrier, whenever the carrier is empty of ampoules therein.

14. A machine for sealing ampoules, comprising a sealing means, a power means, a rotatable ampoule carrier the said carrier being freely spun or turned on its own bearings by a finger touch; a pair of pulleys with a friction-belt upon them, mounted contiguous to the sealing means, and unconnected with any part of the carrier or its mechanism, and constructed and arranged to frictionally contact the exteriors of the ampoules in the carrier which are contiguous to and in the travel of the belt are approaching the sealing means, and solely by such contact, and by the mounting of the ampoules directly in the carrier, rotate said ampoules approaching the sealing means and only those, and also thereby and by the friction of the ampoules in the insides of the carrier recesses which they occupy, impart translatory rotatory circular motion to said carrier; and means comprising an offset in the carrier recesses, for tipping the ampoules to a slight angle in said recesses, to frictionally engage them more firmly therein against pulling out, and also grip the said carrier as they rotate therein and carry it with the belt.

15. In a machine for sealing ampoules of the class described, a rotatable ampoule carrier, a power means normally wholly unconnected with said carrier and unable to rotate it, a pair of pulleys with a friction-belt around them, also unconnected with any part of the carrier or its mechanism and unable to rotate it while empty of ampoules, and contacting directly the exterior surfaces of an ampoule or ampoules contiguous to and approaching the sealing means, and simultaneously rotating said ampoule or ampoules and also through their friction with the carrier body in such rotation drive the carrier body along with the belt without any separate rotating means or parts added to the carrier to accomplish said dual rotation by one means.

16. In a machine for sealing ampoules of the class described, a rotatable ampoule carrier, a power means normally wholly unconnected with said carrier and thereby unable to rotate it, a pair of pulleys with a friction-belt around them, also unconnected with any part of the carrier or its mechanism and unable to rotate it while empty of ampoules, and contacting directly the exterior surfaces of an ampoule or ampoules contiguous to and approaching the sealing means, and simultaneously rotating said ampoule or ampoules and also through their friction with the carrier in such rotation drive the carrier along with the belt without any separate rotating means or parts added to the carrier to accomplish such dual rotation by one means; the said carrier being provided with recesses in its body

75 in which the ampoules fit and in fitting grip the

inside of the said recess and thereby the body of the carrier rotatably by friction, and said recesses being offset or advanced in one part, relatively to the other part, whereby to provide an additional leverage of the ampoule in and against the walls of the said recesses.
